UNITED STATES PATENT OFFICE.

WILLIAM F. BIBLE, JR., OF GREENEVILLE, TENNESSEE.

STIRRUP.

1,113,093.

Specification of Letters Patent.

Patented Oct. 6, 1914.

Application filed February 18, 1914. Serial No. 819,591.

To all whom it may concern:

Be it known that I, WILLIAM F. BIBLE, Jr., a citizen of the United States, residing at Greeneville, in the county of Greene and State of Tennessee, have invented certain new and useful Improvements in Stirrups, of which the following is a specification, reference being had to the accompanying drawings.

10 This invention relates to new and useful improvements in stirrups, and more particularly to that type known as safety stirrups.

In riding, a horse often becomes unmanageable and there is great danger of the 15 rider being thrown with his foot engaged in the stirrup in such manner that he is liable to be dragged over the ground and meet with serious injury or possibly with death.

20 It is, therefore, the object of the present invention to provide a stirrup which is so constructed that in case of an emergency it will, by a peculiar movement of the operator's foot in the stirrup, immediately be 25 actuated to release the foot from all connection with the stirrup and to allow the rider to fall clear of the horse.

20 A further object of the invention resides in the provision of such a device which presents no obstruction to the operation of the 30 stirrup in its normal use and which is associated with the stirrup in such a manner that the design thereof is not marred.

It is further the object of the invention to 35 provide such a device which comprises a minimum number of simple parts so that it will prove durable and efficient in use and can be manufactured at a comparatively low cost.

40 With the above and other objects in view, the invention resides more fully in the novel combination, formation and arrangement of parts more fully hereinafter described and, particularly pointed out in the claim hereto 45 appended.

Reference is had to the accompanying drawings in which similar characters of reference designate corresponding parts throughout the several views and wherein—

50 Figure 1 is a side elevation of a stirrup constructed in accordance with the present invention. Fig. 2 is a vertical sectional view through the stirrup on the line 2—2 of Fig. 1, looking toward the releasing means of the 55 stirrup, the shield plate being removed. Fig. 3 is a view similar to Fig. 2 but show-

ing the shield plate in place. Fig. 4 is a top plan view of the stirrup.

Referring to the drawings, there is shown a stirrup embodying two legs, each consisting of two members 5, 5^a 6 and 6^a, the members 5^a and 6^a being connected by a foot tread 7^a which is integral with the members. The members 5 and 6 are connected by the usual cross bar 7 carrying a roller 8, the latter to be engaged by an ordinary stirrup strap. The members 6 and 6^a are connected by a hinge at their point of juncture 9, so as to permit the member 5^a, tread 7^a and member 6^a to swing away from the member 6 in case of accident, as will hereinafter more fully appear.

The inner face of the member 5 is provided with a recess 12 in which is pivoted the lower end of a curved lever 16 by a bolt 19 which extends through the member 5 to its outer side and has its protruding end upset. The lower end of the lever 16 is formed into a dog 17 that is designed to interlock with a catch 15 carried by the upper end of a plate 13, the lower end of which is formed into a head that is seated within the inner face of the member 5 and held firmly assembled therewith by bolts 14. In order to maintain the dog and catch normally in locked engagement, a spring 18 is employed which is firmly riveted at its upper end to the inner wall of the recess 12, and bears at its lower end against the outer face of the dog adjacent to the dog 14. In order to conceal and protect the dog, catch and spring 18, a shield 20 is provided which is rigidly secured to the inner face of the member 5 and extends downwardly to the point of juncture 11 between this latter member 95 and the member 5.

Pivottally connected to the member 6 by a bolt 23 disposed in alinement with the bolt 19 is a second curved lever 22, that is the counterpart of the lever 16, except that it is devoid of the dog 17, and these two levers are connected by a releasing bar 21 rigid with the outer terminals of the two levers, and serve to hold the same rigidly connected and out of contact with the inner faces of the legs members 5 and 6.

It is to be understood, that in use, the releasing bar 21 will be disposed over the instep of the user of the stirrup, so that in the event of being thrown, or of the horse running away, any upward movement of the foot will cause a like movement to be im-

parted to the releasing bar, whereupon the dog 17 will be thrown out of locked engagement with the catch 15, permitting the lower section of the stirrup to drop and thereby 5 release the foot of the rider.

The improvements herein described are simple in character, will be found thoroughly efficient for the purposes designed, and will in a ready manner prevent accidents which might otherwise occur with the 10 ordinary form of stirrup.

Having thus described this invention, what is claimed is:

15 A stirrup comprising two two-part legs, the lower members of which are connected by a tread, and the upper members by a stirrup strap receiving bar, a hinge connecting the two members of one of the legs, a catch carried by the lower member of the

other leg, the upper member of the latter 20 leg being provided in its inner face with a recess to receive the head of the catch, a pair of curved levers pivotally connected with the upper members of the two legs, a releasing bar connecting the two levers, a 25 dog carried by the lower end of one of the levers and disposed within the recess and arranged to engage the catch, a spring coacting with the lever to hold the catch and dog normally in locked engagement, and a shield 30 for inclosing the catch dog and spring.

In testimony whereof I heretunto affix my signature in the presence of two witnesses.

WILLIE F. BIBLE, JR.
